UNITED STATES PATENT OFFICE.

LEE P. HYNES, OF CHICAGO, ILLINOIS, ASSIGNOR TO RAILWAY UTILITY COMPANY, OF CHICAGO, ILLINOIS, A CORPORATION OF ILLINOIS.

VENTILATOR.

1,223,390.

Specification of Letters Patent. Patented Apr. 24, 1917.

Application filed May 31, 1913. Serial No. 770,886.

To all whom it may concern:

Be it known that I, LEE P. HYNES, a citizen of the United States, residing at Chicago, in the county of Cook and State of Illinois, have invented certain new and useful Improvements in Ventilators, of which the following is a specification.

My ventilator is designed more particularly for use in connection with railroad and other cars, though as will be readily understood from the following detailed description thereof it is applicable to use in connection with other compartments, rooms and buildings to be ventilated. The present device is intended and designed for the purpose of admitting air into a room or compartment and is ordinarily, though not necessarily, used in connection with some provision for the outlet or exhaust of the air therefrom. A number of disadvantages have been found in connection with the intake ventilators heretofore in use, among which may be mentioned that many of them permit a direct draft of air to enter the rooms with which they are connected causing danger of cold and other ailments, while others of them either have no provision for the exclusion of dirt, leaves, snow, etc., or where such provision is made they are apt to become stopped up or clogged by the accumulation of such materials. It is the object of my invention to construct a ventilator which furnishes a large volume of air from which the dirt, etc., is screened and separated, and provides for automatically getting rid of the latter. In the accompanying drawings and in the following specification I have disclosed two embodiments of my invention which differ in respects which will be later pointed out and are the most suitable and advantageous forms at present known to me. It is to be understood, however, that my invention is not limited to these specific forms which are shown and described in detail for the purpose of exemplification only, but its scope is determined by the following claims in which I have endeavored to distinguish the invention from the prior art so far as known to me without, however, relinquishing any part thereof.

In the accompanying drawings Figure 1 is a perspective of so much of a car body as is necessary to understand my invention with the latter applied thereto; Fig. 2 a vertical longitudinal section of the car body

and ventilator upon the line 2—2 of Fig. 3; Fig. 3 a vertical transverse section of the same upon the line 3—3 of Fig. 2; Fig. 4 a perspective of a second form of my invention shown as attached to a car; Fig. 5 a side elevation thereof, and Fig. 6 a transverse vertical section of the same upon the line 6—6 of Fig. 5.

Each part is designated by the same reference character throughout the several views.

Referring first to that form of my invention shown in Figs. 1, 2 and 3 and to said figures, the car may be of any usual and approved construction of that type having a deck sash 7 to which the ventilator is directly attached. The ventilator comprises a flange or attaching plate 8 for securing it to the deck sash which is cut away at 9 for the passage of air therefrom into the car, the cut-away portion being in use in register with a similar cut-away section of the sash. Preferably the opening above referred to is covered with fine wire netting to exclude any foreign matters which notwithstanding the construction to be presently described may reach this opening. The ventilator also comprises an outer wall 10 suitably spaced from the flange plate 8 and connected thereto by a bottom plate 6 and top plate 11. Preferably these parts are all made of sheet metal though any material suitable for the purpose may be used. The bottom plate 6, as shown more particularly in Fig. 2, is bent into two curved wings or sections 12, 13 which meet centrally of the plate in a ridge 14 and fall away upon opposite sides thereof forming deflectors either of which is active according to the direction of the air current. The ridge 14 rises nearly to the bottom of the outer opening through the flange plate above described. The top plate 11 is bent downwardly and inwardly at its opposite ends to form the deflectors 15, 16 which extend below the level of the opening through the flange plate 8 and to about the level of the ridge or apex of the bottom plate.

With the car moving in the direction of the arrow A, Fig. 2, or in case of a stationary construction with the wind blowing in the opposite direction, air is caused to flow in the direction of the arrows B, Fig. 2, against the plate 13 by which it is deflected upwardly and through the opening in the flange plate into the car. A portion of the

air, however, escapes beyond the ridge 14 through the opening between the walls 12, 15 as indicated by the dotted arrow, Fig. 2. Any dirt, leaves, snow or foreign matter striking upon the entering section 13 of the bottom plate is retarded in its motion and in case the draft is sufficient rises along the same and drops over the ridge or apex 14 upon the other side where it is carried away by that portion of the air current 10 which spills over the ridge and escapes as set forth above; and also any foreign matter which by reason of any unusual strength of the air current is carried upward beyond the ridge drops beyond the same, owing to 15 loss of velocity of the air current and escapes. Thus there is provided an ample volume of fresh air which is freed from heavy impurities and enters the car gently 20 by reason of its changes in direction and the screen interposed in its path and without sufficient violence to be injurious to the occupants. As shown in Fig. 3 the wall of the car is double at this point though this 25 does not materially affect the ventilator structure, and within the car is provided with a closure or damper 17 for the opening 17' carrying a pawl 18 coacting with the rack 19 by means of which the position of the damper may be regulated.

In function and operation the modification disclosed in Figs. 4, 5 and 6 is substantially identical with that described above, but it is somewhat changed in construction 35 to adapt it to be used on the curved roof of a so-called turtle deck car. In this modification the flange plate 8' is curved to conform to the shape of that portion of the roof 7' to which it is applied and cut away at 9', the opening being arranged 40 when in use in registry with a similar opening in the roof of the car. When the latter is double or hollow, as shown in Fig. 6, the opening in the flange plate is provided 45 with a boxing 19 which extends from one wall of the roof to the other and is covered at the end within the car by a perforated plate 20. The front and rear ends of the ventilator casing are partially closed by end 50 plates 22, 22 (see Fig. 4) which extend downwardly from the cover plate to the top of the vertical wall 10'. The plate forming the bottom of the air passages is ridged as in the earlier described construction at 14' 55 and the sections or wings 12', 13' upon opposite sides of the ridge likewise fall away in concave curves forming deflectors but

their shape is modified to conform to the modified shape of the ventilator casing. In this modification the screen 23 is arranged 60 in a horizontal plane at a suitable distance above the ridge to permit some of the air entering the device spilling over the ridge without passing through said screen.

As above stated the operation of this form 65 of ventilator is substantially identical with that of the form shown in Figs. 1, 2 and 3 but the air deflected from the bottom plate strikes against the horizontal screen and on passing therethrough is deflected by the 70 cover plate 11' into the car. In this modification the damper 17' is shown located in the plane of the flange plate 8' or substantially in that of the outer wall of the roof 75 and its position is regulated by a handle 24 provided with a rack 25 and spring-pressed finger 26 which resists movement of the handle but permits it under sufficient pressure.

I claim:

1. An intake ventilator having a longitudinal passage open at both ends, an outlet passage in one of the side walls thereof and a transverse deflecting abutment in the bottom of said passage. 80
2. An air intake or ventilator having a longitudinal passage open at both ends, a transverse horizontal deflecting abutment intermediate the ends of the passage and an outlet opening in one of the side walls thereof of intermediate the ends of the passage and above the abutment. 85
3. An air inlet or ventilator having a longitudinal passage open at both ends and an intermediate outlet in one of the walls thereof, an abutment intermediate the ends of the passage and adapted to deflect the entering current of air, and end walls or abutments projecting from the wall of the passage opposite the first mentioned abutment and extending toward the same. 90

4. A ventilator or air inlet having a longitudinally extending passage open at both ends, and an intermediate outlet, a transverse ridge extending upward from the bottom of the passage and adapted to deflect an entering current of air, and end walls extending downward from the top of the passage substantially to the level of the top of the ridge. 105
